(57) **CLAIM**

The ornamental design for an anchor insertion device, as shown and described.

DESCRIPTION

FIG. 1 is a perspective view of an anchor insertion device showing our new design;

FIG. 2 is a front view of the device of FIG. 1;

FIG. 3 is a back view of the device of FIG. 1;

FIG. 4 is a left view of the device of FIG. 1;

FIG. 5 is a right view of the device of FIG. 1;

FIG. 6 is a top view of the device of FIG. 1; and,

FIG. 7 is a bottom view of the device of FIG. 1.

The broken lines shown in the drawings depict portions of the anchor insertion device that form no part of the claimed design.

1 Claim, 4 Drawing Sheets
